AUTOMATIC SAW SHARPENER

Henry Anton Hamberger, Rochester, N. Y., assignor to Hamco Machines, Incorporated, Rochester, N. Y., a corporation of New York

Application June 23, 1955, Serial No. 36,648

Term of patent 14 years

(Cl. D37—1)

Fig. 1

Fig. 2

Fig. 1 is a perspective view of the automatic saw sharpener taken from the front and showing my new design; and

Fig. 2 is a perspective view of the automatic saw sharpener shown in the preceding figure and taken from the rear thereof.

The saw blade shown in Fig. 1 is for the purpose of illustration.

I claim:

The ornamental design for an automatic saw sharpener, as shown and described.
